UNITED STATES PATENT OFFICE.

ALVIN E. BUCHENBERG, OF TOLEDO, OHIO.

GENERATOR.

Application filed July 14, 1917, Serial No. 180,672. Renewed April 17, 1923.

To all whom it may concern:

Be it known that I, ALVIN E. BUCHENBERG, a citizen of the United States, residing at Toledo, in the county of Lucas and State 5 of Ohio, have invented certain new and useful Improvements in Generators, of which I declare the following to be a full, clear, and exact description.

This invention relates to improvements 10 in generators and particularly to automatic means for regulating the output of the generator.

In electric starting and lighting systems 15 for automobiles, there is not as great a drain on the storage battery in warm weather or in a warm climate, as in cold weather or a cold climate, due to the fact that the engine starts more quickly and there is less use for the lighting system, moreover the ampere 20 hour capacity of the battery is reduced with decrease in temperature. It is highly desirable to provide means for regulating the output of the generator so that this output will be decreased in warm weather, when 25 there is less drain on the storage battery, and so that the generator will operate at its maximum output in the cool weather, when such maximum output is desirable.

An object of this invention is to provide 30 automatic means, controlled by atmospheric temperature for regulating the output of the generator. A further object of my invention is to provide temperature responsive means for adjusting the third brush of a 35 generator provided with the third brush system of regulation.

Further objects, and objects relating to economies of manufacture and details of construction, will definitely appear from the 40 detailed description to follow.

I accomplish the objects of my invention by the devices and means described in the following specification.

A structure constituting a preferred embodiment of my invention is illustrated in the accompanying drawing forming a part of this specification, in which:

Figure I is a sectional view through the casing of a generator, showing in end elevation a structure in which my invention is embodied.

Figure II is a view in end elevation of a third brush equipped with automatic controlling means constructed in accordance 55 with my invention.

Figure III is a plan view of the blank from which the bracket, in which the third brush is mounted, is constructed.

Figure IV is an enlarged, detail, sectional view taken substantially on the line IV—IV 60 of Figure II; and, Figure V is a view similar to Figure IV, but showing a slightly modified form of my invention.

In the drawings, similar reference numerals refer to similar parts throughout the 65 several views, and the sectional views are taken looking in the direction of the arrows at the end of the section lines.

In accordance with the theory of the third brush system of regulation for generators 70 the output of the generator may be decreased by movement of the third brush in a direction opposite to the direction of rotation of the armature, while the output may be increased by movement of the third brush in 75 the direction of rotation of the armature. According to my invention I provide a heat-responsive element, which is so mounted and connected with a movably mounted third brush, as to move the third brush relative 80 to the armature whenever there is any increase in the temperature of the air surrounding or within the generator.

The brush holder ring 12 is secured to the end wall 11 of the casing 10 by means of the 85 bolts 13 passing through the slots 14 in ears extending from said brush holder ring. The fixed brushes 16 are mounted in the brush holder brackets 15, which are carried by the ring 12, in the usual manner. The third 90 brush is mounted in a bracket comprising the U-shaped portion 17, with the ears 18 on each side thereof, said bracket being adjustably secured to the ring by means of the bolts 19, passing through said ears 18 and 95 through the slot 20 in the brush holder ring. The flanges 21 are struck in from the sides of the part 17 and engage the brush 22 at opposite sides so that the brush may rock upon the edges of said flanges as a fulcrum, 100 as appears from Figure IV of the drawing. The tail 23 extends from one of the ears 18 rearwardly and has, at its rear end, an upturned finger 24, in which the bolt 25 is mounted. A curved bi-metallic strip 26 has 105 one end thereof secured to and clamped between the nuts carried on the bolt 25. The opposite end of said bi-metallic strip is mounted in the notch 27 formed in the side of the U-shaped portion 17 of the bracket, so 110

that the free end on said strip engages the brush 22 at a point a slight distance removed from the fulcrum thereof.

This strip is made of two strips of different metal secured together, said metals being such that they have different coefficients of expansion, such, for instance, as brass and steel. As a result, any change in temperature will result in a movement of the curved strip, as indicated by dotted lines in Figure IV. The unequal coefficients of expansion of the curved strip cause it to straighten out and move out of its normal curved position, so that, as the temperature increases, the curved bi-metallic strip 26 will tend to occupy the position shown in dotted lines in Figure IV, and the free end thereof will tend to push the brush 22 to one side, rocking it on its fulcrum on the edges of the flanges 21, so as to move it relative to the armature. Fingers 28 and 29 are struck upwardly from the bracket and the finger 28 is offset relative to the finger 29, and one end of the coiled spring 30 is mounted between the fingers 28 and 29, the other free end of said spring 31 engaging the end of the brush 22 so as to yieldingly hold it in engagement with the commutator and to tend to return it to its normal position when the bi-metallic strip is contracted to its normal position.

I have shown, in Figure III, a plan view of the blank from which the bracket carrying the third brush is made, and the manner in which the bracket is formed from this blank will be apparent from the inspection of the view without further description, it being apparent that the blank is slit where indicated by full lines, and is creased or folded where indicated by dotted lines.

In Figure V I have shown a modification of my invention, in which the brush 22 is mounted between the flanges 34, struck inwardly from the sides of the U-shaped portion 32 of the bracket which, as in the other form of my invention, is secured to the brush holder ring by the bolts 19. A bi-metallic strip has one end thereof bent laterally and secured to the side of the U-shaped portion 32 of the bracket while the other end is secured to the free end of lever 38 having a head 39, which engages the end of the brush 22. The bracket 38 is provided with the fingers 28 and 29, between which the end of the spring 30 is mounted, the other end 31 of said spring engaging the head 39 of the lever 38, as shown in Figure V of the drawing. It will be apparent that, as this bi-metallic strip 35 expands due to heat, it will swing as shown by dotted lines in Figure V, tilting the brush holder on its fulcrum and moving the brush in a direction opposite to the direction of rotation of the armature.

From the description of the parts given above, the operation of my device should be very readily understood.

In Figure IV I have shown in full lines the position of the brush which may be called the position of maximum output. That is, the position in which the brush will be adjusted and designed to operate in the coldest weather, which is likely to obtain. The bi-metallic strip 26 may be adjusted on the bolt 25, so as to permit the brush to stand in the position shown in full lines. It will be apparent then, that, as the temperature adjacent the brush increases, the unequal expansion of the parts of the bi-metallic strip 26 will cause the same to alter its position so that the free end thereof will swing the brush on its fulcrum between the edges 21 of the flanges, so as to tilt the brush and move it in a direction opposite to the direction of rotation of the armature, thus decreasing the output of the generator. As the temperature decreases, the bi-metallic strip will return to its first position and the spring 31 engaging the end of the brush will tend to return it to its original position, so it will be seen that I have provided temperature controlled means for positioning the third brush relative to the armature, so as to regulate automatically the output of the generator.

In the modification of my invention, shown in Figure V, the same principle is involved, but it is worked out in a slightly different way, the arrangement of the bi-metallic strip and the connection between the bi-metallic strip and the brush being slightly different. In this modification of my invention, the end of the brush is secured within the head portion 39 of the lever 38, and the unequal expansion of the parts of the bi-metallic strip 35 causes it to swing to one side, as shown in dotted lines in Figure V, so as to tilt the brush 22 on its fulcrum between the edges of the flanges 34.

I am aware that the particular embodiment of my invention, here shown and described, is susceptible of considerable variation without departing from the spirit of my invention, but I have found that this particular embodiment is desirable from many standpoints, and, therefore, I desire to claim the same specifically as well as broadly as indicated by the appended claims.

Having thus described my invention, what I claim as new and desire to secure by Letters Patent is—

1. In a dynamo-electric machine having a commutator, and a pair of main brushes, an adjustable third brush and temperature controlled means responsive to the temperature of said machine for varying the position of said third brush.

2. In a dynamo-electric machine having a commutator, and a pair of fixed main brushes, a third brush, means whereby the position of said third brush may be manually adjusted and supplemental means controlled

- by temperature for adjusting said third brush.
3. In a dynamo-electric machine having a commutator, a brush supporting device having a main brush, a third brush movably mounted on said device and temperature controlled means carried by said brush supporting device for moving said third brush relative to said main brush.
- 10 4. In a dynamo-electric machine having a commutator, a member encircling said commutator for supporting a plurality of brushes, a third brush adjustably mounted on said member and temperature controlled means comprising a plurality of strips of different kinds of metal carried by said member and co-operative with said third brush to adjust its position in response to changes in temperature in the vicinity thereof.
5. In a dynamo-electric machine, the combination of a brush, a holder therefor and temperature responsive means for moving said brush in said holder.
- 25 6. In a dynamo-electric machine having a commutator, the combination of a brush, a holder therefor, resilient means for pressing said brush against said commutator and temperature responsive means for moving said brush in said holder.
- 30 7. In a dynamo-electric machine having a commutator, the combination of a brush, a holder therefor, a spring carried by said holder for pressing said brush against said commutator and means responsive to the temperature of the surrounding medium for moving said brush in said holder.
- 35 8. In a dynamo-electric machine, the combination of a brush holder, a brush therein, temperature responsive means secured to said holder and engaging said brush to rock the same in said holder.
- 40 9. In a dynamo-electric machine, the combination of a brush, a holder therefor having means to permit a rocking movement thereof, a bi-metallic member secured to said holder and engaging said brush to rock said brush with changes in temperature.
10. In a dynamo-electric machine, the combination of a brush, a holder therefor having means for loosely holding said brush, a spring carried by said holder for pressing against said brush, and a bi-metallic member also carried by said holder and engaging said brush to rock the same in response to changes in temperature of the surrounding medium.
- 15 11. In a dynamo-electric machine, having a commutator, a frame, a supporting ring surrounding said commutator, a pair of brush holders secured to said ring, main brushes carried by said holders, means for adjustably securing said ring to said frame to permit a rotative movement about said commutator, a third-brush holder carried by said ring, means permitting adjustment of said third-brush holder on said ring, a third brush mounted in said third-brush holder to have a limited rocking movement, means for pressing said third brush against said commutator, and a bi-metallic strip carried by said third-brush holder and engaging said third brush for rocking the same in response to changes in temperature of the surrounding medium.
- 20 12. In a machine of the class described, the combination of a bracket; a third brush carried thereby, so as to tilt relative thereto; temperature-controlled means carried by said bracket for tilting said third brush; and spring means for returning said third brush to normal position.
- 25 13. In a machine of the class described, the combination of a bracket; a third brush carried thereby, and fulcrumed therein; and temperature-controlled means carried by said bracket for rocking said third brush on its fulcrum.
- 30 14. In a machine of the class described, the combination of a third brush; a bracket carrying said third brush, said third brush being movable relative to said bracket; and heat-responsive means carried by said bracket for moving said third brush.

In testimony whereof I affix my signature.
ALVIN E. BUCHENBERG.
